US0D1087149S

(12) United States Design Patent (10) Patent No.: US D1,087,149 S
(45) Date of Patent: * Aug. 5, 2025

(54) DISPLAY SCREEN OR PORTION THEREOF
WITH GRAPHICAL USER INTERFACE

(71) Applicant: Fisher & Paykel Healthcare Limited,
Auckland (NZ)

(72) Inventors: Benjamin Wilson Casse, Auckland (NZ); Christopher Harding Campbell, Auckland (NZ); Katarzyna Sobolewska, Auckland (NZ); David Robert Keith Walker, Auckland (NZ)

(73) Assignee: Fisher & Paykel Healthcare Limited,
Auckland (NZ)

() Term: 15 Years

(21) Appl. No.: 29/866,920

(22) Filed: Sep. 30, 2022

Related U.S. Application Data

(62) Division of application No. 29/738,671, filed on Jun. 18, 2020, now Pat. No. Des. 967,157, which is a division of application No. 29/600,193, filed on Apr. 10, 2017, now Pat. No. Des. 890,783.

(74) Attorney, Agent, or Firm — Knobbe, Martens, Olson & Bear, LLP

(57) CLAIM

The ornamental design for a display screen or portion thereof with graphical user interface, as shown and described.

DESCRIPTION

The FIGURE is a front view of a display screen or portion thereof with graphical user interface showing our new design.

The broken lines, including those showing a display screen or portion thereof and those depicting portions of a graphical user interface, form no part of the claimed design.
